UNITED STATES PATENT OFFICE.

ERNEST DERIHON, OF LIEGE, BELGIUM, ASSIGNOR TO THE SOCIÉTÉ ANONYME USINES DERIHON, OF LONCIN-LEZ-LIEGE, BELGIUM, A CORPORATION OF BELGIUM.

SHOCK ABSORBER FOR MOTOR CARS AND OTHER SUSPENDED VEHICLES.

Application filed February 2, 1922. Serial No. 533,638.

To all whom it may concern:

Be it known that I, ERNEST DERIHON, engineer, a subject of the King of Belgium, residing at 364 Rue St. Laurent, 5 Liege, Belgium, have invented certain new and useful Improvements in Shock Absorbers for Motor Cars and Other Suspended Vehicles, of which the following is a specification, reference being had therein to 10 the accompanying drawing.

My Patents Nos. 1068329 of 1912; 1068330; 1183281 of 1912; 1290115 of 1919 and 1290116 of 1919 describe particularly an arrangement comprising valves carried by two 15 blades or vanes in one piece, which is made movable as compared with a fixed wall in an oil cylinder, in such a way that one or other of these valves opens according to the direction of movement from the intermediate position of the spring. The part of the cylinder comprised between each of the two blades or vanes (placed in the intermediate position) and the fixed wall is bored to a 20 diameter greater than that of the circumference described by the outer edge of the blades or vanes, with the object of allowing the blade or vane, which has been brought into that part, to oscillate without any resistance, whilst the other blade or vane, entering at this moment the exactly fitting cylindrical part, then acts as a piston on the 25 return of the blade or vane towards the intermediate position.

The use of valves, of which my above 30 patents make mention, can be dispensed with by the use of the following arrangement, which is shown by way of example in the annexed drawing.

Figure 1 shows a cross section through 35 A—B in the cylinder of the absorber (Figure 2).

Figure 2 shows a longitudinal section through C—D (Figure 1).

The apparatus is composed of an oil cylinder 1 divided at the middle by a cross partition 2. The blades or vanes 3 and 4, which are solid with the central hub 5 move in the cylinder 1 from one side to another of the partition 2 round the axle 6.

As in the above patents the cylinder 1 is 40 fixed to the chassis of the vehicle, whilst the blades or vanes 3 and 4 are connected to the

axis of the vehicle by means of a suitable lever and joint, which are not shown on the drawings.

The blades or vanes 3 and 4 are provided with an indentation which produce openings such as those at 7, and which are closed alternately by a central part 8, fitted with slight friction to the cylindrical part 9 of the central hub 5. This arrangement dispenses with the valves which were formerly fitted to the bottom faces of the blades or vanes 3 and 4.

The removable part 8 oscillates freely on 55 the end of the shaft, which itself is solid with the hub 5, which in turn, is solid with the blades or vanes 3 and 4.

The oscillation of the part 8 thus produces alternately the openings 7, and replaces with advantage the working of the valves.

In the above example, communication between the two compartments of the cylinder 1 is established by ducts 10 formed in the 60 interior of the cylinder 1 to left and right of the partition.

It will be readily understood from what is said above that, when the spring of the vehicle is compressed or distended, the blades or vanes 3 and 4 swing round the axle in such a way as to hit alternately on the faces 11 and 12 of the blades or vanes 3 and 4 of the part 5, so as to close or clear the openings such as 7.

When the opening 7 of the blade or vane, which travels upwards, is exposed, the blade or vane, which travels downwards, forms the corresponding opening 7 and clears the duct 10, which establishes communication between the two compartments of the cylinder 1. At this moment, no braking action is set up, but during the return movement the opening 7 of the blade or vane, which is going downwards again, closes again and sets up a constant braking action, whatever may be the amplitude of the displacement of the blades or vanes 3 and 4.

Having now particularly described and ascertained the nature of my said invention 90 and in what manner the same is to be performed I declare that what I claim is:—

A shock absorber for motor-cars and other suspended vehicles, allowing free compres-

sion and free distension of the suspension spring and only braking the return movement towards the intermediate position, characterized by the fact that the hub, which
5 is solid with the blades or vanes carries, with a slight friction fit, a shutter or member the opposite ends or wings of which come alternately into contact with the corresponding

parts of the blades or vanes in such a way as to act as valves.

10

In testimony whereof I hereunto affix my signature.

ERNEST DERIHON.
